UNITED STATES PATENT OFFICE.

LOUIS BEEH, OF PLAINFIELD, NEW JERSEY, ASSIGNOR TO ROBERT BOSCH AKTIEN-
GESELLSCHAFT, OF STUTTGART, GERMANY.

IMPULSE STARTER FOR IGNITION APPARATUS.

Application filed August 5, 1924. Serial No. 730,297.

This invention relates to impulse starters for ignition apparatus of the type employing two coupling parts, one affixed to a driving shaft and constituting the driving coupling part and the other affixed to the shaft of the rotor of the ignition device and constituting the driven coupling part. The invention more particularly relates to such a device in which the temporary locking of the rotor of the ignition apparatus is effected by pawls attached to the driven coupling part and engaging in their working position the rear face of a stationary abutment provided on the casing of the ignition device. Throwing the rotor forward is effected by a spring connecting the driving part of the coupling to the driven part when the pawls are lifted off the abutment by projections arranged on the coupling-part which is affixed to the driving shaft. The pawls are devised to form fly-bodies, so that they, at a certain definite rate of revolution of the driving shaft, move outwardly beyond the range of the stationary abutment on the casing of the ignition device under the action of the centrifugal force. Then the movement of the rotor by jerks or impulses and its uniform rotation commences.

30 A primary object of the invention is to do away with the drawback experienced with the known impulse starters of the kind in question of one or another of the pawls falling back from its position of disengagement into its working position due to shocks while the ignition device is in full operation, whereby either the impulse starter is exposed to the risk of being destroyed or the possibility arises of stalling the motor by reason of the sudden retarded ignition which is a consequence of the sudden locking of the rotor.

40 Another object of the invention is the provision of means to put the impulse starter out of action completely, for instance for adjusting or re-adjusting the ignition device.

Accordingly, the invention provides means which are adapted to prevent the levers or pawls from attaining locking position except at the desired predetermined times. In the preferable form of my invention I provide a slide-path for the pawls restraining them from movement to locking position and

which is so devised that only a small gap 55 remains between its end and the opposite face of the stationary abutment by which the pawls are retained or locked, whereby the possibility of the swung-out pawls falling back into their working position is only 60 a very small one.

Another improvement consists in the provision of means by which the width of said gap may be varied by adjusting said slide-path. Thereby the range of the number or 65 rate of revolutions within which the impulse starter remains acting can be varied at liberty. The narrower the said gap, the earlier, that is to say at a correspondingly lower number of revolutions, will the movement by jerks of the rotor of the ignition-device cease because the pawls sliding on the slide-path require a certain time to get into their checking or locked position through the gap. If the gap is closed completely or nearly completely, the impulse-starter is put out of action.

With the foregoing objects and principles in view, the invention resides in the novel subject matter hereinafter described and claimed, the description being supplemented by the accompanying drawings, in which—

Figure 1 is an end elevational view of the improved impulse starter, looking toward the ignition apparatus, and with the 85 driving coupling member shown in dotted lines and only in partial view to avoid obstructing an end elevational view of the driven coupling member;

Figure 2 is a similar view showing the 90 starter in another position;

Figure 3 is a view corresponding to Fig. 2 and showing the slide-path combined with adjusting means;

Figure 4 is a partial sectional view of the 95 starter on line A—B of Fig. 2, with the driving coupling member and the spring shown disassembled and in side elevational view, the figure also showing a part of the ignition apparatus in side elevation and the 100 end portion of its casing in section.

The impulse starter consists of two coupling-parts or members 1 and 2, of which 1 is affixed to the driving shaft 3, and 2 to the driven shaft 4 which is the shaft of the 105 rotor of the ignition apparatus 5. The two parts of the coupling are connected with each other by a spring 6, the end 6' of which

is inserted in a hole 7 of the coupling part 1 and the end 6" of which is inserted in a hole 8 of the coupling part 2.

The coupling part 2 is provided with arms 9 carrying pawls 10 having projections 11. The casing 12 of the ignition apparatus 5 is provided with an abutment member 13 serving to retain the pawls 10 and the coupling part 2 connected herewith. An annular member 14 forms a slide-path for the pawls 10 and is preferably combined with a casing 15 for the driving device. The slide-path 14 and the abutment 13 are located in the same circle. The object of the member 14 is to retain the pawls 10 so as to prevent them from moving into the checking or locking position.

Preferably the member 14 may be adjustable. For this purpose an arm 21 may be attached to the sleeve 15 as clearly shown in Fig. 3. This arm is connected with an operating handle by a rod or the like (not shown) in a well known manner. The arm 21 is attached to the sleeve-like casing 15 by a strip or band 22 one end 23 of which is firmly connected with the arm 21 and the other end of which is secured to a member 24 so arranged as to slide in a recess of the lever 21 and to be shifted in said recess 30 by a screw 26 whereby the strip or band 22 is firmly pressed around the casing 15.

The casing 15 is secured to the casing 12 of the ignition apparatus by screws 18. In order to render the casing rotatably adjustable slits 17 are provided through which the screw extend.

Cam projections 20 are provided on the inner face of the driving part of member 1, to release the pawls 10 from locking position, as will more fully appear from the description of the operation of the device, later to be given. In the assembled position of the parts now shown disassembled in Fig. 4, the driving coupling part or member 1 is nested within the casing 15, with the inner face of the member 1 closely adjacent the annular rim of the driven member indicated by the numeral 2 in Fig. 4, and with the cam projections 20 of the member 1 extending inwardly, or to the right as the parts are viewed in Fig. 4, to positions between the arms 9 of the driven member. In Figs. 1, 2 and 3, only the outer rim of the driving member 1 and 55 the cam projections 20 are indicated and by broken lines, in order to avoid obstructing the end elevational view of the driven member 2 and associated parts.

The operation of my improved starter is as follows:

When the shaft 3 is rotated slowly for instance when starting the engine, the pawl 10 which approaches the abutment 13 tends to fall onto hub 16 of the coupling half 2, but it is prevented therefrom by the slide-

path 14, as clearly shown in Fig. 1. When the projection 11 of the lever or pawl 10 gets to the gap 19 between the edge of said slide-path 14 and the abutment 13 the lever or pawl 10 falls into its checking position 70 (Fig. 2) in which the projection 11 is locked by the abutment 13. While the shaft 3 and the coupling part 1 continue to rotate, the coupling part 2 remains stationary. The spring 6 has now been put under tension. 75 After a certain rotation, one of the cams 20 of the coupling-part 1 comes into position immediately beneath the free curved terminal of the retained pawl 10 and lifts it (Fig. 3) from its checking position. Now 80 the coupling part 2 can follow the pull of the spring 6 and is abruptly impelled by it in the direction of rotation of the coupling half 1 until the projections 20 contact with the arms 9. The velocity imparted to the armature 5 by this movement of the coupling half 2 is high enough to cause an efficacious spark.

As soon as the engine has commenced to start, and all rotating parts have attained 90 a certain speed the pawls 10 remain, under the action of the centrifugal force, in their swung-out position in which they are no longer retained by the abutment 13. Only when the speed slows down do they fall 95 back into the positions shown in the figures. Figs. 1, 2 and 3 show clearly that when a pawl is moved by a shock, while the engine is operating at normal speed, 100 from its swung-out position towards the hub 16, it can get into the checking position only when its projection 11 is situated immediately over the gap 19. In any other case, the pawl falling onto the slide-path 105 14 is caused by the centrifugal force to swing outwards again before an unintentional checking can occur.

To adjust the width of the gap 19, the casing 15 is turned after the screws 18 have been loosened; and they may be tightened 110 again after the desired adjustment is finished. When it is desired to adjust the shell 15 without taking the impulse starter apart, the screws 18 are drawn home only to such an extent that the casing 15 remains rotatable around the axis and may be moved by the lever 21. Then it is possible to close completely the gap 19 at any time in order to throw out of action the impulse-starter. The part of the gap effective in permitting the entry of the projection 11 of the pawl 10 into checking or locking position, it will be observed, is completely closed, when the left hand end of the rim element 14, as the parts are viewed 115 in Figs. 1, 2 and 3, is advanced, by rotatable adjustment of the casing 15, into contact with the stationary abutment 13 extending from the casing 12 of the ignition apparatus. 120 130

Although I have shown in the drawings and described in the specification a certain distinct form of the invention, I wish it to be understood that I do not limit myself thereto. It is obvious that changes in detail may be made without departing from the spirit and scope of the invention.

What is claimed is:

1. An impulse starter for magnetos, comprising, in combination, a driven member mounted on the rotor shaft of the magneto, a driving member and a spring connecting said members, a stop positioned adjacent said driven member, a detent pivotally and eccentrically mounted on said driven member and adapted for movement into position for engagement with said stop when said driven member is at rest or slowly rotating, and centrifugally maintained in operative position when said driven member is rotated at relatively high speed, and adjustable restraining means adapted by adjustment to positively restrain said detent from movement to position for engagement with said stop throughout the whole or any desired arc of each cycle of rotary movement of said driven member.
2. An impulse driving device for ignition apparatus, comprising in combination, a rotatable driven coupling part, a driving coupling part, a spring connecting the said driven part and the said driving part, levers pivotally and eccentrically mounted on the said driven part, a fixed abutment on the ignition apparatus adapted to engage said levers in locking position to hold said driven part immovable, projections extending from said driving part and adapted in one driving movement of said driving part to disengage said levers from the locking position, a slide-path restraining said levers from movement into position for engagement with said abutment, said slide-path having a cut out receiving the said stationary abutment.
3. An impulse driving device for ignition apparatus, comprising in combination, a rotatable driven coupling part, a driving coupling part, a spring connecting the said driven part and the said driving part, levers pivotally and eccentrically mounted on the said driven part, a fixed abutment on the ignition apparatus adapted to engage said levers in locking position to hold said driven part immovable, projections extending from said driving part and adapted in one driving movement of said driving part to disengage said levers from the locking position, a slide-path restraining said levers from movement into position for engagement with said abutment, said slide-path having a cut out receiving the said stationary abutment.
4. An impulse driving device for ignition apparatus, comprising in combination, a rotatable driven coupling part, a driving coupling part, a spring connecting the said driven part and the said driving part, levers pivotally and eccentrically mounted on the said driven part, a fixed abutment on the ignition apparatus adapted to engage said levers in locking position to hold said driven part immovable, projections extending from said driving part and adapted in one driving movement of said driving part to disengage said levers from the locking position, an adjustable slide-path restraining said levers from movement into position for engagement with said abutment, said slide-way having a cut out receiving the said stationary abutment, the said cut out being larger than the said abutment.
5. An impulse driving device for ignition apparatus, comprising in combination, a rotatable driven coupling part, a driving coupling part, a spring connecting the said driven part and the said driving part, levers pivotally and eccentrically mounted on the said driven part, a fixed abutment on the ignition apparatus adapted to engage said levers in locking position to hold said driven part immovable, projections extending from said driving part and adapted in one driving movement of said driving part to disengage said levers from the locking position, an adjustable arc-shaped slide-path restraining said levers from movement into position for engagement with said abutment, means for rotatably adjusting the said slide-path from the outside of the driving device, said slide-path having a cut out receiving the said stationary abutment, the said cut out being larger than the said abutment.
6. An impulse driving device for ignition apparatus, comprising in combination, a rotatable driven coupling part, a driving coupling part, a spring connecting the said driven part and the said driving part, levers pivotally and eccentrically mounted on the said driven part, a fixed abutment on the ignition apparatus adapted to engage said levers in locking position to hold said driven part immovable, projections extending from said driving part and adapted in one driving movement of said driving part to disengage said levers from the locking position, a casing surrounding the said coupling parts, and means positively restraining said levers from movement into position for engagement with said abutment during a major portion of each cycle of rotary movement of said driven part, said means being integral with the said casing.
7. An impulse driving device for ignition apparatus, comprising in combination, a rotatable driven coupling part, a driving coupling part, a spring connecting the said driven part and the said driving part, levers
